F. CECKA.

HOSIERY FRAME.

APPLICATION FILED OCT. 16, 1915.

Patented Feb. 27, 1917.

UNITED STATES PATENT OFFICE.

FRANZ CECKA, OF CHEMNITZ, GERMANY, ASSIGNOR TO THE FIRM OF SCHUBERT & SALZER MASCHINENFABRIK, AKTIENGESELLSCHAFT, OF CHEMNITZ, GERMANY.

HOSIERY-FRAME.

1,217,411.

Specification of Letters Patent. Patented Feb. 27, 1917.

Original application filed July 22, 1914, Serial No. 852,417. Divided and this application filed October 16, 1915. Serial No. 56,247.

To all whom it may concern:

Be it known that I, FRANZ CECKA, a citizen of the German Empire, residing at Chemnitz, in the Kingdom of Saxony, Germany, have invented certain new and useful Improvements in Hosiery-Frames; and I do hereby declare the following to be a full, clear, and exact description of the invention, such as will enable others skilled in the art 10 to which it appertains to make and use the same, this being a division of my application, Serial No. 852,417, filed July 22, 1914.

My invention relates to improvements in hosiery frames, and more particularly in the 15 mechanism for reducing and increasing the inward stroke of the thread guide.

When making reinforced portions in knitted goods on flat hosiery frames the inward stroke of the thread guide is limited 20 by means of fixed stops which correspond to the desired breadth of the reinforced portion. By means of such a mechanism only reinforced portions can be made which have straight border lines, while it is not possible 25 to make fancy reinforced portions.

In my copending application Serial No. 852,417 I have shown and described a mechanism by means of which fancy reinforced portions can be made such mechanism consisting in a pair of stop members each adapted 30 to arrest either one of a pair of thread guides and formed on adjacent sides with rack teeth, a pinion arranged between said stop members engaging in the teeth of the racks so as to shift the stop members in opposite directions upon being operated by a pawl and ratchet mechanism. However, with the mechanism described in the said application only such reinforced portions can 35 be made in knitted goods which are of equal breadth all over. In order to be able to gradually increase the reinforced portions to any desired point and to reduce them thereafter and, if desired, increase them again, 40 the mechanism disclosed in said application 45 has to undergo a certain change which shall hereinafter be explained.

The preferred form of a mechanism according to the present invention is represented in the drawings affixed to this specification,

Figure 1 being a diagrammatical view

showing the heel and sole of a stocking made with reinforced portions, and

Fig. 2 a front view showing the modified 55 form of the mechanism by means of which reinforced portions of the form shown in Fig. 1 can be made, in which the breadth of the reinforced portions is increased, from the point E to the point F, and from E' to F', 60 whereupon the breadth remains unchanged along the lines F—G and F'—G', and finally the border lines of the reinforced portions are directed outward and at an angle to the line F—G along the lines G—H and 65 G'—H' according to the increase in the breadth of the blank. Thereafter the border lines follow parallel lines H—I and H'—I', whereupon they are again directed angularly 70 and inward along the lines I—K and I'—K'. Thereafter they follow parallel lines K—L and K'—L', and finally they are directed angularly and toward the middle M of the blank.

In addition to the usual thread guides provided for knitting the non-reinforced parts of the work thread guides 3 and 4 are provided, which coöperate with the said usual thread guides in knitting reinforced portions, as is known in the art. For clearness 80 sake only the thread guides 3 and 4 have been shown, which are secured in the usual way to thread guide bars 1 and 2. The strokes of the bars 1 and 2 are limited at the outer side of the frame by means of stop members 5. 85 To the thread guide bar 1 a stop arm 6 is secured and to the thread guide bar 2 a stop arm 7.

To a shaft 8 a pinion 9 is keyed which is rigidly connected with ratchet wheels 10" and 10'" the diameters of which are larger than that of the pinion. The teeth of the wheels 10" and 10'" are cut in opposite directions. The pinion 9 is in mesh with racks 11' and 12' which are guided in suitable 95 bearings 13. The racks 11' and 12' which are in engagement with the pinion 9 are each provided with a single stop 14' and 16' respectively mounted at opposite ends of the racks. A push rod 20' slidably mounted in suitable guides is constructed with transverse arms 20", 20" to which push arms 36 and 37 are jointed which are connected with links 27' and 27" respectively.

To the lower end of the push member 20' a pivot bolt 23' is secured which provides a support for a sleeve 24' which is non-shiftable thereon and is always in the path of a 5 cam 29' keyed to a shaft 28'.

On a pivot bolt 38 a rocking lever is mounted which consists of two arms 39 and 41. To the arm 39 of the said rocking lever a pin 40 is secured which is located in position 10 for engagement by the push rod 36, and to the arm 41 of the lever a pin 42 is secured which is in position for engagement by the push rod 37. The arm 39 carries a pawl 22' which bears on a pin 21', and the 15 arm 41 carries a pawl 22'' which bears on a pin 21''. Normally the ratchet wheels 10'', 10''' are locked as against rotation in both directions by means of the pawls 33' and 33'', and they are adapted to be released 20 upon operation of the arm 39 or 41 by rods 35' and 35''.

The operation of the mechanism is as follows:

By means of the cam 29' the push member 20' is continuously reciprocated in vertical direction. The push rods 36 and 37 are normally in such positions, that they do not engage the pins 40 and 41. By means of a suitable counting mechanism such as a jac- 25 quard pattern, a narrowing chain, or the like, the push rods 36 and 37 can be rocked to the right and in the direction of the arrow shown in Fig. 2. For example, if the push rod 36 is shifted to the right by the 30 link 27', it engages the pin 40 of the arm 39 when the push rod 20' is moving upward. Thereby the pawl 22' is forced toward the ratchet wheel 10''' so as to advance the same. Thereby the rod 11' is shifted to the left and 35 the rod 12' to the right, so that the stops 14' and 16' are approached to each other, the thread guide bar 1 can move farther to the left and the thread guide bar 2 farther to the right, and the thread guides 3 and 4 are 40 moved toward each other. Thereby the re- forced portions E—F and E'—F' can be 45 made the border lines of which are directed at an angle inward.

If on the other hand the push member 37 is shifted to the right by means of the link 50 27'', it acts on the pin 42 of the arm 41, and

the pawl 22' turns the gear wheel 9 in the opposite direction, so that the stops 14' and 16' of the rods 11' and 12' are separated from each other and the inward strokes of the thread guide bars are shortened. There- 55 by the reinforced portions can be made so as to be directed with their border lines angularly and outward, as is shown in the parts G—H and G'—H'. It will readily 60 be understood that by setting the counting mechanism the stops can be moved in one or the other direction or stopped according to the desired form of the reinforced portion. 65

I claim herein as my invention:

1. In a hosiery frame, the combination with a pair of thread guides having reciprocating movements in opposite directions, of a pair of parallel rods each having a stop 70 arranged for coöperation with one of the thread guides and formed on adjacent sides with rack teeth, a pinion engaging said rack teeth and adapted to shift the rods in opposite directions, pawl and ratchet mechanisms, adapted to rotate said pinion in opposite 75 directions, operating means moving in one direction, and means to connect said operating means with either one of the pawl and ratchet mechanisms. 80

2. In a hosiery frame, the combination with a pair of thread guides having reciprocating movements in opposite directions, of a pair of parallel rods each having a stop 85 arranged for coöperation with one of the thread guides and formed on adjacent sides with rack teeth, a pinion engaging said rack teeth and adapted to shift the rods in opposite directions, pawl and ratchet mechanisms adapted to rotate said pinion in opposite 90 directions, operating means moving in one direction, a rocking lever carrying said pawls at opposite sides of its fulcrum, and means for throwing said operating means into position for rocking engagement with said rocking 95 lever at either one of its ends.

In testimony whereof I hereunto affix my signature in the presence of two witnesses.

FRANZ CECKA.
